FOUNTAIN PEN

Application filed May 17, 1929. Serial No. 363,791.

This invention relates to fountain pens, and has particular reference to certain improvements in fountain pens of that type which are commonly known as safety pens. As previously devised, this type of fountain pen includes a barrel serving as an ink reservoir which is open at one end and closed at the opposite end, together with a nib carrier which permits the nib to be respectively projected from or retracted within the barrel through the open end, the carrier having means for sealing the open end when the nib is projected and a cap being employed to fit over the open end, which cap is provided with means for sealing said open end when the nib is retracted. Pens of this type also include means on the carrier and on an actuator disposed within the closed end of the barrel for effecting movement of the carrier to cause retraction and projection of the nib. This means is usually of the relatively rotatable type, such as a pin extending through the carrier and a spiral slotted portion of the actuator with the ends engaging in a longitudinal slot in the barrel, together with an externally disposed manipulator which extends through the closed end of the barrel.

Pens of the type heretofore outlined are open to certain objections and possess certain defects, notably, the tendency of the same to leak at the point where the externally disposed manipulator extends through and rotates in the barrel, due to wear after limited use.

In order to overcome the above recited disadvantages and defects, the present invention broadly comprehends in a fountain pen of the safety type, means preferably carried by the cap, which is engageable with the nib carrier through the open end of the pen for manipulating the same to effect the projection and retraction of the nib.

More specifically, the invention contemplates in a safety pen of the same general type specified, means such as a key which is preferably carried by the cap and which is adapted to extend through the open end of the barrel for engagement with the nib carrier to effect the projection and retraction of the nib by the actuator upon relative rotation of

the cap and barrel, so that the employment of manipulating means extending through the closed end of the cap may be dispensed with, whereby said end can be permanently sealed against the possibility of leakage.

Other objects of the invention reside in the comparative simplicity of construction and mode of operation of the pen, the economy with which it may be produced and assembled and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a longitudinal sectional view through a pen constructed in accordance with the invention, illustrating the nib retracted and the cap applied.

Figure 2 is a similar view with the nib projected and the cap removed.

Figure 3 is a longitudinal sectional view through the cap removed from the barrel.

Figure 4 is a transverse sectional view taken approximately on the line indicated at 4-4 in Figure 1.

Figure 5 is a similar view taken approximately on the line indicated at 5-5 in Figure 1.

Referring to the drawings by characters of reference, 10 designates the barrel or body of the pen which is of elongated tubular formation and which is provided with an open end 11 having a reduced internal diameter 12 defining an internal frusto-conical shoulder 13 which serves as a valve seat. The outer end of the barrel is formed with an external frusto-conical wall 14 also serving as a valve seat. The opposite end 15 of the barrel 10 is closed in any suitable manner, such as by a plug 16 threaded thereinto. The plug carries a cylindrical sleeve 17 which projects axially inward of the barrel and said sleeve is designed to receive and guide the rear end 18 of a nib carrier 19. The nib carrier may have integrally formed therewith or otherwise provided, a feed piece or element 20 of the

conventional type, over which the nib 21 is arranged and held in place by a collar 22, it being understood that the nib and feed piece 20 extend beyond the collar. For the 5 major portion of its length, the collar is of a diameter approximately equal to the reduced diameter 12 at the open end of the pen barrel. At its rear end, however, the collar 22 is provided with an enlarged outer peripheral 10 flange 23 defining at its juncture with the major portion of the sleeve, a frusto-conical shoulder 24 constituting a valve portion which is adapted to seat against the internal shoulder or valve seat 13 of the pen barrel 15 for establishing a seal at this point to prevent leakage when the nib is projected to the active position illustrated in Figure 2. The carrier 19 and feed piece 20 are longitudinally cut away to provide an ink passage 20 through which the ink is adapted to flow to the nib when the same is in its projected active position.

In order to provide means for effecting longitudinal or axial movement of the carrier 25 19 with respect to the barrel whereby the nib is projected from and retracted within the pen barrel through the open end 11, a radial inwardly projecting pin 26 is provided adjacent the free end of the sleeve 17, and said 30 pin cooperates with a spiral groove 27 cut or otherwise formed in the rear end of the carrier. Obviously, relative rotation of the barrel and carrier 19 due to the pin and 35 groove connection will effect axial movement of said barrel and carrier. In the instant case, the means for holding the carrier against rotation while rotating the barrel, which is the preferred manner of operating the pen, or if desired, for rotating the carrier 40 while holding the barrel stationary, consists of a key or pin 28 which is inserted through the open end of the barrel and which is designed to be received by a keyway or socket 29 formed in the carrier. The key and keyway must of necessity be of non-circular formation and, as specifically illustrated, the key and keyway are disclosed as of a square shape in cross section. The key or pin 28 is preferably rigidly anchored to the pen cap 45 30 and projects axially thereof from the intermediate solid portion 31 of the same. The cap 30 is provided with internal threads 32 which are designed to mate with the external threads 33 on the barrel, whereby the cap is 50 retained in place thereon. As is customary in fountain pens of the safety type, the cap is provided with a valve element 34 which protrudes from the solid portion 31 of the cap and which is adapted to seat on the frusto- 55 conical end wall 14 of the open end 11 of the barrel when the threads 32 have been completely screwed home on the threads 33. The cap 30 in the present instance may be provided with a socket 35 which is designed to 60 afford means whereby the cap may be associated with the closed end of the barrel when the pen is in active use.

In view of the fact that the key or pin 28 may be inserted in the keyway or socket 29 in a plurality of different relative positions, it is obvious that a 70 number of threads 32 and 33 corresponding to the number of positions in which the key may be inserted in the keyway, must be provided and accordingly, as illustrated, four sets of threads 32 and 33 are provided to insure proper engagement of the cap threads with the barrel threads, irrespective of the 75 position in which the key is inserted in the keyway.

In view of the fact that the threads 32 and 33 have a pitch which does not make for rapid feeding or relative movement of the parts, the spiral groove 27 is formed with a set of convolutions 27a which correspond to the pitch of the threads 32 and 33 and with a separate set of convolutions 27b which are of a greater pitch than the convolutions 27a. This, therefore, permits the carrier 19 and nib to be rapidly projected after the threads 32 and 33 have been disengaged, it being 90 understood that during the initial projecting operation the movement of the nib coincides with the relative movement of the barrel with respect to the cap. Likewise, in retracting the nib within the barrel, the initial retracted movement is more rapid than the subsequent movement after the threads 32 and 33 engage.

In operation, with the pen in closed condition, as illustrated in Figure 1, the user 100 preferably grasps and holds the cap 30 stationary and rotates the barrel in a counter-clockwise direction, as viewed from the bottom end. This motion causes the sleeve 17 which turns therewith to move the pin 26 in the convolutions 27a of the spiral groove 27, effecting an outward axial movement of the carrier 19 and pen nib 21, at the same time unscrewing the threads 32 and 33 on the barrel and cap respectively. When the 105 cap and barrel threads 32 and 33 are disengaged, the pin 26 entering the convolutions 27b of the spiral groove 27 forces the pen barrel 10 away from the cap and downwardly with respect to the actuator 19 which is held against rotation by the key 28 engaging in the keyway 29. Obviously, the downward movement of the barrel 10 exposes the nib 21 until the internal shoulder or seat 13 engages the frusto-conical shoulder or valve 110 element 24 of the collar 22. The user has then only to separate the cap and barrel to have the pen in condition for active use for writing. The socketed end 35 of the cap may then be telescopically arranged over 115 the closed end of the barrel. With the cap removed and the pen in writing condition as illustrated in Figure 2, the pen may be closed by engaging the cap over the nib end, at which time the key or pin 28 enters the 120

keyway or socket 29. The operation is reversed and the barrel is turned in a clockwise direction, as viewed from the bottom of Figure 2. The cap is held stationary and by rotating the barrel, the actuator pin 26 of the sleeve 17 follows the convolutions 27b of the spiral groove 27, causing the barrel to move rapidly into the cap until it reaches the point where the threads 32 and 33 re-engage. At this point, the pin passes from the convolutions 27b to the convolutions 27a so that the remaining turning movement of the barrel effects a relative movement of the same with respect to the cap coincident with the screwing operation of the threads 32 and 33. This movement finally causes the valve element 34 to seat on the frusto-conical end 14 of the barrel whereby the pen is in a closed sealed condition. Obviously, this construction and arrangement avoids the necessity of having a rotating element extending through the closed end of the barrel, permitting this end to be sealed to prevent leakage.

In order to guide the user in properly threading or unthreading the barrel and cap to a point where the nib is retracted while the cap and barrel threads are disengaged to permit of the removal of the cap, a suitable annular mark indicated at 36 is provided on the pen barrel with which the free end of the cap is adapted to register. This places the nib in a partially restricted position which permits the removal of the cap so that the barrel of the pen can then be filled with ink by introducing the same through the upper open end of the barrel. After the filling operation, it is, of course, understood that the cap and barrel are again associated with the key extending into the keyway 29 of the carrier and the pen is either projected or retracted as desired. In order to set up a sufficient friction between the rear end 18 of the carrier and the sleeve 17, the said sleeve may be provided with longitudinally extending circumferentially spaced slits 37 providing therebetween portions which may be inherently deflected to produce a tension between the inner periphery of the sleeve and the outer periphery of the rear end 18.

In view of the fact that a small quantity of ink may adhere to the key 28, a depression or pocket 38 is formed in the valve 34 at the point where the key 28 projects therefrom. This will prevent ink which adheres to the key from spreading over the seating face of the valve.

The innermost terminal 27c of the convolutions 27b of the spiral groove 27 is of a lesser pitch or practically straight so that the pressure exerted on the pen nib when writing prevents any possibility of inward movement of the carrier and resulting leak-

age between the valve shoulder 24 and the external seat 13.

What is claimed is:

1. In a fountain pen of the safety type which includes a barrel having a closed end and an open end provided with an internal valve seat, a nib, a nib carrier having a valve shoulder and a spiral groove, a radial pin carried by and disposed within the barrel operative to move the nib respectively to projected and retracted positions upon relative rotation of the barrel and carrier whereby to respectively seat and unseat the valve shoulder with respect to the internal valve seat; means insertable through the open end of the barrel and engageable with the carrier to effect said relative rotation, said means consisting of a key of non-circular cross sectional shape and a socketed portion of the carrier of a cross sectional shape corresponding to the key and adapted to receive the same.

2. In a fountain pen including a barrel constituting an ink reservoir having a closed end and an open end provided with an internal valve seat, a nib, a nib carrier having a valve shoulder and mounted for axial movement within the barrel to move the nib through the open end respectively to projected and retracted positions and to seat and unseat the valve shoulder, coacting devices on the barrel and carrier for effecting relative axial movements thereof upon relative rotation therebetween, a cap and coacting means on the cap and carrier for manipulating the pen to effect the actuation of the coacting devices on said barrel and carrier, said means consisting of a key carried by the cap and an axially socketed portion of the nib carrier within which the key is engageable for turning the same.

3. In a fountain pen of the safety type including a barrel having an open end and a closed sealed end and having an external thread adjacent its open end; a cap having internal threads adapted to engage the externally threaded portion of the barrel and provided with a valve adapted to seal the open end of the barrel, the combination with a nib carrier having a spiral groove and a radial inwardly projecting pin on the barrel coacting with said spiral groove to effect upon relative rotation of the barrel and carrier, axial relative movements of the nib carrier and barrel, said nib carrier groove including convolutions coinciding with the pitch of the barrel and cap engaging threads and convolutions of greater pitch than said barrel and cap engaging threads.

4. In a fountain pen of the safety type including a barrel having an open end and a closed sealed end and having an external thread adjacent its open end; a cap having internal threads adapted to engage the externally threaded portion of the barrel and provided with a valve adapted to seal the

open end of the barrel, the combination with a nib carrier having a spiral groove and a radial inwardly projecting pin on the barrel coacting with said spiral groove to effect upon relative rotation of the barrel and carrier, axial relative movements of the nib carrier and barrel, said nib carrier groove including convolutions coinciding with the pitch of the barrel and cap engaging threads and convolutions of greater pitch than said barrel and cap engaging threads and coacting means carried respectively by the cap and the nib carrier to effect relative rotation between said carrier and barrel upon relative rotation of the cap and barrel.

5. In a fountain pen of the safety type which includes a barrel having a closed end and an open end provided with an internal valve seat, a nib, a nib carrier having a valve shoulder and a spiral groove, a radial pin carried by and disposed within the barrel operative to move the nib respectively to projected and retracted positions upon relative rotation of the barrel and carrier whereby to respectively seat and unseat the valve shoulder with respect to the internal valve seat; means insertable through the open end of the barrel and engageable with the carrier to effect said relative rotation, said means consisting of a key of non-circular cross sectional shape and a socketed portion of the carrier of a cross sectional shape corresponding to the key and adapted to receive the same, the said nib carrier groove having its inner extremity of lesser pitch than the pitch of the remaining convolutions for preventing movement of the carrier by the writing pressure of the nib.

6. In a fountain pen of the safety type which includes a barrel having a closed end and an open end provided with an internal valve seat, a nib, a nib carrier having a valve shoulder and a spiral groove, a radial pin carried by and disposed within the barrel operative to move the nib respectively to projected and retracted positions upon relative rotation of the barrel and carrier whereby to respectively seat and unseat the valve shoulder with respect to the internal valve seat; means insertable through the open end of the barrel and engageable with the carrier to effect said relative rotation, said means consisting of a key of non-circular cross sectional shape and a socketed portion of the carrier of a cross sectional shape corresponding to the key and adapted to receive the same, the said nib carrier groove having its inner extremity of such a pitch as to prevent inward movement of the carrier by the writing pressure.

7. In a fountain pen of the safety type including a barrel having an open end and a closed sealed end and having an external thread adjacent its open end; a cap having internal threads adapted to engage the externally threaded portion of the barrel and provided with a valve adapted to seal the open

end of the barrel, the combination with a nib carrier having a spiral groove and a radial inwardly projecting pin on the barrel coacting with said spiral groove to effect upon relative rotation of the barrel and carrier, axial relative movements of the nib carrier and barrel, said nib carrier groove including convolutions coinciding with the pitch of the barrel and cap engaging threads and convolutions of greater pitch than said barrel and cap engaging threads and coacting means carried respectively by the cap and the nib carrier to effect relative rotation between said carrier and barrel upon relative rotation of the cap and barrel, said means consisting of a multi-faced axially projecting key on the cap and a multi-faced axial socket in the nib carrier.

8. In a fountain pen of the safety type including a barrel having an open end and a closed sealed end and having an external thread adjacent its open end; a cap having internal threads adapted to engage the externally threaded portion of the barrel and provided with a valve adapted to seal the open end of the barrel, the combination with a nib carrier having a spiral groove and a radial inwardly projecting pin on the barrel coacting with said spiral groove to effect upon relative rotation of the barrel and carrier, axial relative movements of the nib carrier and barrel, said nib carrier groove including convolutions coinciding with the pitch of the barrel and cap engaging threads and convolutions of greater pitch than said barrel and cap engaging threads and coacting means carried respectively by the cap and the nib carrier to effect relative rotation between said carrier and barrel upon relative rotation of the cap and barrel, said means consisting of a multi-faced axially projecting key on the cap and a multi-faced axial socket in the nib carrier and said coacting cap and parallel threads being equal in number to the number of positions in which the key and socket may be interengaged.

Signed at New York in the county of New York and State of New York this 15th day of May, 1929.
